UNITED STATES PATENT OFFICE.

ALBERT BACK, OF NEW YORK, N. Y.

DESIGN FOR NECK-RUCHING.

Specification forming part of Design No. **11,153**, dated April 15, 1879. Application filed February 10, 1879.
[Term of patent 7 years.]

To all whom it may concern:

Be it known that I, ALBERT BACK, of the city, county, and State of New York, have invented a new and Improved Design for Neck-Ruching, of which the following is a specification.

The object of this newly-designed ruching is to provide a new ornamental effect by giving it two or more folds or sides parallel to each in the direction of the length of the ruching, but at any angle when viewed from the end.

A front and end view of each of several forms of this design is shown in the photographs.

In A the ruching is single and turned over at a right angle, presenting two sides. In B the ruching is double, presenting three sides or lines, numbered consecutively, exclusive of the binding. C shows the sides placed at a slightly-different angle from B. D shows one fold of the ruching straight up, the second fold being bent to form the two sides of a triangle. E shows them bent at right angles, forming a square in cross-section. In F one fold is bent out to a right angle about midway, the other remaining straight. G shows one fold straight, the other bent back at an obtuse angle. H

shows both folded over in the same direction, forming two right angles. I is bent in four angles, forming an irregular figure. In J the two folds form a triangle. K is the same, slightly varied; and in L a similar arrangement is shown. In all these forms the fold or folds are arranged so as to present parallel sides running in the direction of the length of the ruching, whereby an ornamental effect is given to it that greatly enhances its appearance.

Having thus described my invention, what I claim as new, and desire to secure by Design Patent, is—

A design for neck-ruch, consisting of parallel folds running across an angular piece of material and alternately on opposite sides up to the vertex of the angle, each fold being reversed in position at said vertex, so as to take its place on the opposite side of the material, as shown in the accompanying illustration.

ALBERT BACK.
